UNITED STATES PATENT OFFICE.

HARVEY G. RUE, OF HIGHTSTOWN, NEW JERSEY.

DEVICE FOR CUTTING OR DIVIDING PILLS OR PELLETS.

SPECIFICATION forming part of Letters Patent No. 599,796, dated March 1, 1898.

Application filed May 24, 1897. Serial No. 637,951. (No model.)

To all whom it may concern:

Be it known that I, HARVEY G. RUE, a citizen of the United States, residing at Hightstown, in the county of Mercer and State of New Jersey, have invented certain new and useful Improvements in Devices for Cutting or Dividing Pills or Pellets, of which the following is a full and complete specification, such as will enable those skilled in the art to

10 which it appertains to make and use the same.

This invention relates to devices for cutting or dividing pills or pellets into proper size before they are rolled into a round form; and the object thereof is to provide an improved device of this class which is simple in construction and operation and which is provided with a plurality of blades and with means for adjusting the same with reference to each other and at the same time always 15 holding said blades in proper relative position or so that the spaces between the same will be even or equal.

The invention is fully disclosed in the following specification, of which the accompanying drawings form a part, in which—

25 Figure 1 is a plan view of my improved pill or pellet cutter, showing the blades in their closest position; Fig. 2, a similar view showing the blades separated to the farthest extent; and Fig. 3, an end view of the apparatus, looking in the direction of the arrow a in Fig. 1.

In the drawings forming part of this specification the separate parts of my improvement are designated by the same numerals of reference in each of the views, and in the practice of my invention I provide an apparatus of the class herein specified, which consists of two horizontal and parallel side bars 30 5, which are connected at one end by a cross-bar 6 and at the opposite end with triangular plates 7.

The side bars 5 are composed of two separate parts, (shown in Fig. 3,) and one of the 35 triangular end plates 7 is of the same thickness as the cross-bar 6 at the opposite end, while the other is much thinner, as is also shown in Fig. 3. The inner sides of the wider ends of the triangular plates 7 are cut away 40 at an angle, as shown at 8 in Fig. 1.

Mounted transversely of the frame and be-

tween the separate parts of the horizontal side bars 5 thereof are longitudinally - movable transverse bars 9, which project at each side of said frame and are provided at one end 55 with blades 10, and these longitudinally-movable bars 9 are of the same thickness as the end plate or bar 6 of the frame, and enough of said bars are employed to fill when close together about one-half of the frame. I also 60 mount in said frame a plurality of longitudinal bars 11, which equal in number the transverse bars 9 and which extend longitudinally of the frame and which exactly fill the space between the side bars 5, and each one of the 65 longitudinal bars 11 is connected with one of the transverse and longitudinally - movable bars 9, as shown at 12, this connection being preferably a rigid connection, and by means of this arrangement the line of connection 70 between the horizontal bars 11 and the transverse longitudinally-movable bars 9 is a diagonal line extending from one side of the frame across the same and terminating at about the middle of the frame on the opposite side, as is clearly shown in Fig. 1, this description being applicable to the device when the transverse and longitudinally - movable bars 9 are in the position shown in Fig. 1 or adjacent to the end of the frame in which the 75 plate or bar 6 is placed.

Pivotedly connected with that side of the frame adjacent to the blades 10, as shown at 13, is a lever 14, which is provided with a central longitudinal slot 15, and each of the longitudinal bars 11 is provided with a pin 16, and said pins 16 project through the slot 15 in the lever 14, and when the parts are in the position shown in Fig. 1 the pins 16 also occupy a diagonal line which extends in a direction opposite to that of the line of the connection of the longitudinal bars 11 with the transverse bars 9.

The operation of this device will be readily understood from the foregoing description 95 when taken in connection with the accompanying drawings and the following statement thereof.

By manipulating the free end of the lever 14 the transverse and longitudinally-movable bars 9 may be forced into the position shown in Fig. 1, in which the transverse bars are 100

close together, or said transverse and longitudinally-movable bars 9 may be moved into the position shown in Fig. 2, in which they are separated, and the space between the 5 blades 10 may thus be enlarged or lessened, as desired, it being understood that the friction of the pivotal connection of the lever 14 with the frame of the apparatus may be made such that the parts will remain in any position in which the lever 14 is set.

One of the transverse bars 9, preferably at about the middle of said bars, is provided with a guide or brace 17, which is secured thereto and which fills the space between the 15 longitudinal bar 11 connected therewith and the adjacent side of the frame, the object of this brace or guide being to retain the parts in proper relative position, and the longitudinal rod or bar 11 adjacent to the side of the 20 frame over which the free end of the lever 14 projects also serves to keep the longitudinal bars 11 in proper position, as will be readily understood.

It will be understood that the blades 10 25 serve to cut the material from which the pills or pellets are made, and these blades may be of any desired width in cross-section, and it will thus be seen that I accomplish the object of my invention by means of a device which 30 is simple in construction and operation and which is well adapted to produce the result for which it is intended, and it will be apparent that changes in and modifications of the construction herein described may be made 35 without departing from the spirit of my invention or sacrificing its advantages.

The end plates 7 need not be triangular in form, but I prefer this construction in order that said plates may form coils for the longitudinal bars 11; but it will be understood 40 that the entire frame may be rectangular in form, in which event the end plates 7 may be made as wide as desired, and the inner edges thereof may be cut away at one side, as shown

at 8, so as to provide greater space for the 45 movement of the lever 14.

Having fully described my invention, I claim as new and desire to secure by Letters Patent—

1. The herein-described device for cutting 50 material for pills or pellets into proper sizes, said device consisting of an oblong frame in which is mounted a plurality of transverse and longitudinally-movable rods or bars, and a corresponding number of longitudinal and 55 longitudinally-movable rods or bars, said longitudinal and transverse rods or bars being connected, and said transverse rods or bars being provided at one end with cutting-blades, and said frame being provided with a lever 60 which is pivotally connected with one side thereof, and in which is formed a longitudinal slot, and said longitudinal bars being each provided with a pin which projects through said slot, substantially as shown and de- 65 scribed.

2. The herein-described apparatus for cutting the material from which pills or pellets are formed into proper sizes, said apparatus consisting of an oblong frame, in which are 70 mounted a plurality of transverse and longitudinally-movable bars, each of which is provided at one end with a cutting-blade, said frame being also provided with a corresponding 75 number of longitudinal and longitudinally-movable rods or bars, said longitudinal rods or bars and said transverse rods or bars being connected as described, and means for operating said longitudinal bars, substantially as shown and described. 80

In testimony that I claim the foregoing as my invention I have signed my name, in presence of the subscribing witnesses, this 3d day of May, 1897.

HARVEY G. RUE.
